MINING METHOD

Philip B. Bucky, Larchmont, N. Y.

Application June 22, 1946, Serial No. 678,614

13 Claims. (CL. 262—1)

1

This invention provides a new and economical method for mining ore that may be used for working both underground deposits and those that crop on the surface. The new method is particularly satisfactory for mining orebodies in regions where the orebody and the ground in which it occurs tends to spall or fail into open spaces, and where wall failure dilutes the broken ore with waste rock. However, it may be used for mining any deposit where it is advantageous to provide support for the ground during or after mining operations. The invention further provides for obtaining improved ore fragmentation in the stope being mined, and for withdrawing the ore from the stopes without dilution by waste rock or fill.

The preferred embodiment of the new method may be termed the "shrink-fill" method of mining, as it involves first breaking the ground by a modified shrinkage method of stoping, and then introducing waste fill at the top of the stope as the fragmented ore is withdrawn from the bottom and as its upper surface subsides within the stope. However, other methods than shrinkage methods may be used, in appropriate cases, to break the ground.

Many different methods for extracting ore from mineral deposits are known and employed. The choice of the particular method to be used in mining any given ore deposit is mainly a matter of selecting the most economical method to which the deposit lends itself, taking into account such factors as richness of the ore, the ease with which it may be broken to permit its withdrawal, the size of the deposit, and the mechanical strength of both the orebody and the ground within which the deposit occurs. Shrinkage methods of mining often are employed. A typical shrinkage method involves digging into the deposit at a depth below its upper surface, and breaking the ore down from the roof of the working space. If the surrounding ground is strong, it is generally sufficient to continue breaking ore from the roof of the stope and withdrawing the broken ore from the bottom of the stope at the proper rate to provide working space for the men until the upper limit of the stope is reached. During the ore-breaking operations the upper surface of the broken ore serves as the floor of the working space, and withdrawal of the broken ore is regulated to maintain a working space of proper height. Thereafter the broken ore is simply withdrawn from the stope, leaving an open cavity underground.

If the surrounding ground is not sufficiently

2

strong to stand unsupported when an open stope (or cavity) is formed within it, some method of supporting the ground and/or preventing dilution of the ore must be provided. This is also important in regions where precautions must be taken against ultimate surface subsidence, because even strong ground may ultimately cave into open emptied stopes.

Numerous methods for supporting the surrounding ground from which ore has been mined are known and employed. Some such methods involve extensive use of timbers to support the ground during mining operations and subsequently. Often the spaces between the timbers are filled with waste rock after the ore has been extracted to provide permanent support for the ground. Considerable handling of small batches of broken ore and fill material usually is required in mining by these methods. The timbering and the handling of ore and fill make such methods expensive, and consequently they are generally used only for mining high grade deposits.

In the so-called "cut-and-fill" method, the ore is usually broken from the stope roof (as in the typical shrinkage method described above), and after one cut of ore has been taken from the roof of the working space and has been withdrawn by shovelling, scraping, or other means, waste fill is introduced to take the place of the ore removed and to raise the floor of the working space high enough to permit another cut to be taken. This method saves the expense of timbering, but involves laborious handling of broken ore and waste fill.

Caving methods which involve breaking the ore simply by allowing it to cave into an undercut opening are generally the most economical methods for underground mining, but such methods can be used only where the ore is of such character as to break properly by caving, and where surface subsidence of the ground is not important.

The new mining method provided by the present invention is generally applicable where shrinkage, cut-and-fill, block caving, and similar methods have heretofore been employed, and is also applicable in many instances where extensive timbering, or timbering and fill, has been considered necessary to support the surrounding ground.

Briefly the new method comprises breaking the ore throughout the height of a stope within an orebody and withdrawing the broken ore by gravity flow through a chute at the stope bottom. In a preferred embodiment of the invention, the ore is broken down from the solid mass of ore in

55

place while the space between it and the previously broken ore is very much smaller than has been maintained in heretofore known mining methods. In general the upper surface of the column of broken ore in the stope is maintained sufficiently close to the lower surface of the overhanging unbroken ore so that any space therebetween is no greater than will be filled substantially completely by material broken in the succeeding blasting (ore-breaking) step. Advantageously, in some cases the upper surface of the broken ore may at all times be maintained substantially in contact with the roof formed by the overhanging mass of unbroken ore. In this manner, the force of the blasting operation by which the solid ore is broken also contributes to further fragmenting the underlying already broken ore. The drilling and other mining operations are conducted from working positions within a rather small manway, so that working conditions are safer than is possible when the mining operations are conducted in relatively large underground open working spaces.

After the ore has been broken throughout the height of the stope, waste fill is added at the top of the stope at substantially the same rate as the broken ore is withdrawn through the chute at the bottom of the stope, and as the upper surface of the broken ore subsides therein. Thus the stope is maintained substantially full of broken material (ore or fill) at all times.

Withdrawal of the broken ore through the chute at the bottom of the stope is continued, with continuing addition of waste fill at the top of the stope, until the interface between the ore and the waste fill reaches the level at which the angle from the ore withdrawal chute to the laterally most remote part of the ore-fill interface is less than about 70° to the horizontal. Further withdrawals of ore by gravity flow then are most advantageously made through another chute located at a point such that said angle is appreciably greater than about 70°.

The new method is generally more economical and in its preferred embodiment may be employed with greater safety than is generally the case with heretofore known mining methods such as those briefly described above. The new method is applicable to orebodies which dip but gently from the horizontal and equally to orebodies which dip steeply. It may be employed successfully in mining large orebodies of great width and length, as well as in mining relatively small orebodies. It is especially useful in mining ore from deposits occurring in ground which is weak and tends to cave or spall in open stopes, and where provision must therefore be made to avoid contamination of the ore and to provide support for the ground, but it may also be used in regions where the ground is strong. The new mining method is peculiarly effective for preventing "rock bursts," a type of ground failure that often occurs in open mining cavities in strong ground. However, the new method may be employed in mining ore from deposits in strong ground, even where rock bursts do not occur, in order to insure permanently against caving and surface subsidence after the deposit has been mined out.

The invention is described in some detail below with reference to the embodiments diagrammed in the accompanying drawings. These embodiments illustrate characteristic and preferred features of the new method, but do not by any means exhaust the modifications that may

be made in adapting the new method to particular ore deposits. In the drawings,

Figs. 1, 2, 3 and 4 show successive stages in mining ore by the new method from a steeply dipping, rather narrow deposit; and

- 5 Fig. 5 shows an adaptation of the new method to the mining of ore from an essentially horizontal deposit of considerable extent that outcrops on the surface.
- 10 10 In the embodiment shown in Figs. 1 to 4, ore is being mined by the new method from a steeply dipping deposit or orebody 10. Preparatory to mining the ore, crosscuts 11 are driven from the mine shaft (not shown) to the orebody. Level drifts 12 also are driven alongside the orebody at vertical intervals of say 50 to 300 or more feet to permit ready access to the orebody. Crosscuts 13 extend out from these level drifts into the orebody. Ore chutes 14 are driven upwardly from the level drifts 12 into the ore deposit at an angle preferably somewhat greater than the angle of repose of broken ore from the orebody.

- 15 After the preliminary development, the ore in the stope that has been marked out by the development work is broken sufficiently so that it may flow by gravity through the chutes 14 and into mine cars for transporting it to the mine shaft, through which it is hoisted to the surface. The chutes 14 are, of course, provided with the usual gates to control the flow of broken ore from the stope.

- 20 25 30 35 35 Breaking the ore may be accomplished in any desired fashion. It may, for example, be broken by the conventional shrinkage method described above, or if the ore is of proper caving quality, it may be broken by a caving method. Generally, however, I prefer to employ the modified and improved shrinkage method illustrated in the drawings and described below.

- 40 45 50 55 60 Figs. 1 to 4 show successive stages in the progress of ore-breaking operations. For purposes of illustration, it is assumed that the ore is to be broken in a series of stopes, arranged one above the other, and each of about the height from one level drift 12 to the next level drift above. In carrying out the method, a raise 15 is first driven along the foot wall of the orebody throughout the height of the stope, from one working level to the next above. As shown in Fig. 1, the raise 15 has been completed throughout the height of the upper stope and a considerable portion of the ore 16 in this stope has already been broken. The corresponding raise in the stope next below is in the course of being driven upwardly. The raises 15 provide the working space from within which the ore-breaking operations are conducted, and may be placed wherever, and in whatever numbers, most advantageous for working the deposit.

- 65 70 75 80 85 90 Before breaking ore within a stope, an open face at the bottom of the stope is obtained by excavating an opening 17, say six to eight feet in height, extending advantageously from the foot wall to the hanging wall and the length of the stope. Drill holes 18 then are driven across the orebody from the raise 15 at an appropriate distance above the bottom surface of the unbroken ore in the stope. The drill holes are loaded, tamped and fired to blast the ore down from the roof. A limited and controlled amount of broken ore then is withdrawn through the chute 14. The amount withdrawn is considerably less than has heretofore been considered necessary, and in general is such that any space thereby created between the upper surface of the broken ore and

the lower surface of the overhanging unbroken mass (such as the spaces 17a in the upper and intermediate stopes in Figs. 1 and 3) is no greater in volume than will be filled by ore broken in the next succeeding blasting operation. In some cases the amount of ore withdrawn is no greater than sufficient to create voids in the mass of broken ore, without lowering the upper surface of the broken ore substantially out of contact with the overhanging roof of unbroken ore (as indicated at 17b, Fig. 4). Another line of drill holes then is driven into the ore mass from the raise 15 above the preceding set of holes. These in turn are loaded and fired, and the operations are repeated until the ore has been broken throughout the height of the stope.

A particular advantage of the foregoing method of breaking the ore results from maintaining the upper surface of the broken ore as close as practical to the still unbroken roof of ore in place. This advantage is that the force of the blast not only breaks ore from the solid roof, but serves also to cause additional fragmentation of the broken ore lying directly below the roof. The improved fragmentation of the ore thereby obtained reduces any tendency for the ore to be blocked in the chutes by large lumps, and otherwise facilitates handling the ore underground. It also facilitates crushing and grinding in subsequent preparation of the ore for treatment to recover its valuable components. Another advantage is that the working space is within the confines of the raise 15. The mining operations can be conducted from this position with greater safety than is possible if such operations must be conducted from working positions in an underground opening of substantial extent. Still another advantage is that the stope is maintained full or nearly full of material at all times, without such open spaces as normally are provided for working purposes, so that the walls of the stope, and to a considerable extent the roof of unbroken ore, are well supported at all times throughout the mining operations. Spalling of weak walls and consequent dilution of the ore, and rock bursts such as occur in strong ground, are thereby prevented.

The appearance of the workings after all of the ore has been broken in the upper stope and as ore-breaking operations are commencing in the intermediate stope is shown in Fig. 2. Advantageously the roof 19 of the upper stope is shaped as shown in the drawings, so that it forms an angle with the horizontal greater than the angle of repose of the fill material subsequently to be introduced. The ore from this stope may now be withdrawn as required through the upper chute 14, and may be transported to the mine shaft for hoisting to the surface.

Concurrently with or subsequently to breaking the ore in the upper stope, ore-breaking operations may be similarly carried out in the intermediate or lower stopes, as illustrated in Figs. 2, 3 and 4. The only difference in procedure in working in the lower stope, as compared with working in the uppermost stope, is that the ore-breaking operations in the lower stope are carried all the way up to the point of breaking through into the stope next above.

After the ore has been broken all the way to the top of the uppermost stope, continued withdrawal of broken ore through the chutes 14 will cause the upper surface of the broken ore 16 to subside from the top of the stope. This subsidence will create an open cavity within the ore

deposit. If this open cavity assumes substantial proportions, the surrounding ground, particularly if it is weak or tends to spall, is likely to cave into the opening thus created, mix with the ore, and lessen its value. Such caving may also render development drifts in the caved region unusable and tend to cause subsidence of the earth at the surface of the ground. Large openings greatly increase the hazard of rock bursts, and may prevent mining in adjacent unworked sections of the orebody.

To prevent such difficulties due to large openings underground, waste fill is introduced into the stope through a suitable opening or chute leading to the apex of its inclined roof 19. The waste fill is supplied to the top of the stope at substantially the same rate and in substantially the same amount as broken ore is withdrawn through the chute or chutes 14 and as the upper surface of the broken ore subsides within the stope. The amount of waste fill thus introduced is sufficient to maintain the stope in which the ore has been broken substantially full of broken material (fill or ore) at all times. The fill and broken ore prevent caving or spalling of the surrounding ground to any appreciable extent, when the ground is weak, and prevent rock bursts when the ore and surrounding rock are strong.

By forming the roof 19 of the stope at an angle greater than the angle of repose of the fill material, fill introduced at the apex of the roof will flow out against the roof and provide support for it as well as for the walls of the deposit.

Any available material may be used as fill. Barren rock from development drifts, or tailings from a concentrator plant located near the mine, often are available and are well-suited for use as fill. The fill may be brought to the stope through the upper level drift 12 and crosscut 13, and may be dumped into the stope through waste chutes provided for this purpose. If desired, such waste chutes may extend all the way to the surface of the ground, so that fill may be introduced into the stope directly from the surface.

I have found that the waste fill may be added directly on top of the broken ore, and that as the ore is withdrawn through the chutes with consequent subsidence of the interface between the waste fill and ore, little or no intermixture of the waste with the ore will occur until the ore-fill interface approaches the chute more closely than a predetermined distance. This distance is the height the interface must be above the ore chute so that the angle from the chute to the laterally most remote part of the interface is 70° (more or less, as best determined by experiment). When withdrawing ore that has been broken throughout the height of several successive stopes, as illustrated in the drawings, I therefore prefer to regulate withdrawing of the ore as follows:

When the interface between the ore and fill has subsided in the upper stope to a level where the angle from the upper stope chute to the laterally most remote part of the interface is no more than about 70° to the horizontal, withdrawal of ore through that chute is discontinued. The upper limit of the dotted line 20 in Fig. 3 indicates the level of the ore-fill interface at the time when withdrawal of ore through the upper chutes 14 is discontinued.

The angle indicated above to be about 70° does not under all circumstances have precisely this value. It may vary considerably one way or the other, depending in general on the flow charac-

teristics of the broken ore, but ordinarily it is at least a little greater than the angle of repose of the broken ore. It may be determined quite accurately for any particular ore by experiment. In referring to that part of the interface which is "laterally most remote" from the chute, I mean, of course the laterally most remote part of the interface that tends to funnel toward the chute in question as the interface subsides evenly. In the case of a wide stope, served by several chutes on the same level, the "laterally most remote" part of the interface in the direction of another chute, may be taken as being along a line midway between the chutes.

After the interface between the ore and waste fill has reached the level below which it is inadvisable to continue withdrawing ore through the upper chute 14, further withdrawal of the broken ore may be effected through the chute at the bottom of the next lower stope (the intermediate stope, as shown in the drawings). When the subsiding interface between the ore and fill reaches the level (indicated by the upper limit of the dotted line 21 in Fig. 4) where the angle from this chute to the laterally most remote part of the interface is again 70° more or less, withdrawal through the intermediate chute is discontinued, and further withdrawal is effected as through the chute at the bottom of the lowermost stope, after the solid portion between stopes is fragmented.

As a result of the above-described procedure for withdrawing this ore, the subsiding interface between the ore and added fill retains substantially the shape of the top of the upper stope at which the fill is added, until the interface reaches the level at which the angle from the lowermost chute to the laterally most remote part of the interface is about 70° .

In withdrawing the ore through the chute or chutes at the bottom of the lowermost stope, the withdrawal may be continued even after the interface between the ore and fill has subsided to below the level corresponding to that at which withdrawal operations through the higher level chutes were discontinued. Indeed, withdrawal through the lowermost chute may continue until waste fill shows in the ore chute, which then indicates that substantially all of the ore has been withdrawn from the stope, and that it contains little but waste fill. There will, however, remain a volume 22 of ore (occupying the region below the dotted line 23 in Fig. 4), which cannot be withdrawn by gravity flow through the lowermost chute 14. This ore, and any small underlying mass of unbroken ore, may be either left in place or mined by special methods.

The new mining method as described above may be used to mine concurrently several stopes within the same ore-body. For example, in mining a steeply dipping orebody such as illustrated in Figs. 1 to 4, mining operations may be proceeding in stopes at several levels at the same time. In this way, the rate at which ore is mined from the deposit may be increased. The height of the stope to be worked may in fact be determined in part from the number of different stopes that it is desired to work concurrently for purposes of obtaining a large daily output of ore.

Fig. 5 illustrates an adaptation of the new method to mining concurrently in several adjacent stopes in an essentially horizontal orebody which outcrops on the surface. As shown in this figure, the orebody 30 is of height H and adjacent stopes 31, 32, 33 and 34 are in various stages of

working. A main haulageway 35 is driven in the rock 49 beneath the orebody, and ore chutes 36 extend from it into the orebody.

Stope 34, as shown in the drawings has been marked out and prepared for mining by driving a manway raise 37 through the stope and opening the ore chutes 36, but ore-breaking has not begun in this stope. In stope 33 ore is being broken by a shrinkage method of the character described previously. The working space for ore-breaking operations is in the manway raises 37. Drill holes 38 are made from setups in the raises 37 (they may be made by long-hole diamond drills) to permit placing of the explosive charges in the overhanging solid ore. Broken ore 45 is withdrawn from the stope through the chutes 36 as required to create voids in the mass of broken ore after each blast, as described above. The bottom of each stope is shown formed with a sloping bottom so that the ore may feed directly into chutes 36 and into the cars or conveyor on the main haulage drift 35.

Stope 32 is shown as it appears after the ore has been broken all the way to the surface and initial addition of fill has been placed on top of it. During subsequent operations in this stope, ore is withdrawn by gravity flow through chutes 35 leading to the main haulageway 35. Waste fill is introduced at the surface at substantially the same rate as broken ore is withdrawn, so as to maintain the stope full at all times of broken material.

The left-hand stope 31 is shown in Fig. 5 as it appears after nearly all of the broken ore therein has been withdrawn through the ore chutes 36 communicating with the main haulageway. Waste fill has been introduced at substantially the same rate as broken ore has been withdrawn, so that the stope has been maintained full of broken material. The fill is introduced directly on top of the broken ore, as I have found that no timber matting or other separating means at the interface 46 of broken ore and fill is necessary to prevent dilution of the ore by the fill as the ore is withdrawn and as the interface 46 subsides within the stope. In fact, withdrawal of the ore results in quite even subsidence of the interface 46 between the broken ore and fill, with little or no intermingling of these broken materials. After completion of the ore-drawing operations (when waste appears in the ore chute), some broken ore 41 and some solid ore 42 may still remain in the stope (as shown for example in stope 31). These residual volumes of ore are small, and may be left in place or may be mined by special methods.

An important feature of the stoping operations illustrated in Fig. 5 is the maintenance of partitions 43 of ore in place between the stopes 31, 32, 33, etc. These partitions (which constitute only a small portion of the ore body) prevent broken ore in one stope from intermingling by cross flow with waste fill added to an adjacent stope, with consequent dilution of the broken ore. In the absence of partitions, cross flow will occur both during the ore-breaking operations and subsequently, if the mining operations in one stope are substantially farther advanced than in the adjacent stope. In addition to resulting in dilution of the broken ore, such cross flow would seriously hamper conduct of the mining operations. The partitions 43, besides preventing cross flow of fill and broken ore, serve as pillars for helping support the ore in place while ore-breaking operations are in progress.

If it is desired to recover all of the ore from the orebody and not leave any ore in place as partitions, it is often possible to erect timber partitions in the course of the ore-breaking operations. When this is done, substantially all of the ore in the deposit may be broken and recovered, but in such event the distance between broken ore and roof must be increased and drilling may take place in the stope (as in conventional shrinkage-stoping operations). It is also possible to add cementing material (such as Portland cement) to the fill material at the stope boundaries, to enable the fill to stand, and when this is done mining operations may be conducted in a subsequently worked adjacent stope so as to break and extract all of the ore up to the cemented fill. This procedure also avoids the need for leaving any partitions of ore in place.

To insure substantially complete extraction of the broken ore from the stope when mining in accordance with the method described herein, it is sometimes advantageous if the bottom of the stope inclines downwardly to a bottom apex at an angle best determined by experiment, but which approximates 70° to the horizontal. The ore chute should of course communicate with the stope through this bottom apex. This angle is indicated in Fig. 5 as that of the boundary between the residual volume of broken ore 41 and the added waste fill in stope 31. So long as the interface between the broken ore and added fill is sufficiently high above the bottom of the stope, it will subside substantially horizontally as the ore is withdrawn. Near the bottom of the stope, however, the broken material, if followed by fill, funnels to the ore chute at an angle of about 70°, more or less. As the substantially horizontal interface between the broken ore and fill enters the region toward the bottom of the stope where this funneling occurs, it too will begin to assume a funnel shape with its apex pointing downwardly toward the ore chute. If the bottom of the stope is horizontal, or less than the above stated angle, some broken ore then will remain in place while waste fill funnels through it to the ore chute. By sloping the bottom of the stope at 70° or such other angle near 70° as is indicated by experiment, there will be no opportunity for this funnel of broken ore to form and in consequence no broken ore will be left in the stope. With stopes having a properly sloped bottom, the appearance of waste fill in the ore chute is a sign that essentially all of the broken ore has been extracted. If the ore is of sufficient value, the sloping bottom of the stope may be formed entirely in the barren rock underlying the ore deposit, and all of the ore may then be broken and extracted.

The new mining method herein described, by providing for addition of waste fill at the top of the stope as broken ore is withdrawn from the bottom, greatly simplifies the mining operations. In contrast to the cut-and-fill method of mining, the new method avoids the need for much hand mucking or scraping of ore, and handling and evening of added fill. Yet it is generally applicable to mining in orebodies adapted to the cut-and-fill method. It is also applicable in some cases to orebodies heretofore mined by stopes heavily timbered to support the surrounding ground. When adapted to such orebodies, the new method saves greatly on the amount of timber required and on the cost of installing the timber.

Once stoping operations reach the point where

fill is introduced, ore may be withdrawn steadily and at any desired rate from the stope until virtually all of the ore has been extracted. No heretofore known method that provides adequate support for the surrounding ground has achieved this advantage. In general, the economies effected in mining operations conducted in accordance with the invention are greater than can be achieved under comparable conditions by any other method which provides effective and permanent support for the surrounding ground.

It is of course evident that the advantages of some features of the invention may be had without making full use of all of the features of the complete new method. For example, it is possible to derive the benefits of adding fill at the top of the stope while withdrawing ore from the bottom regardless of what method of breaking the ore was employed. Hence if desired ordinary shrinkage stoping, caving, or other conventional ore-breaking procedure may be followed. Similarly the benefits of the improved ore-breaking procedure herein described may be obtained without adding fill at the top of the stope after completing the ore-breaking operations, if there is no objection to leaving an open empty stope underground.

The significant features and advantages of the new mining method herein described may be briefly summarized as follows:

The modified shrinkage method for breaking the ore that is advantageously (but not necessarily) employed in connection with the other features of the invention is principally characterized by withdrawing a minimum amount of ore through the chutes after each blasting operation. The amount withdrawn is considerably less than heretofore considered necessary and in many cases need not result in lowering the upper surface of the broken ore substantially out of contact with the overhanging unbroken ore. It is desirable to have the distance between broken ore and unbroken roof as little as possible. With this procedure the following benefits accrue:

1. The men always work in a small relatively safe space, such as the raises shown in the drawings, and not under a large open span in a stope. In addition, a minimum number of openings is required to work an orebody by the new method, and the openings required are of minimum dimensions. This makes the new method particularly safe, and reduces to a minimum the amount of expense involved in ventilating and cooling the mine workings.

2. The broken ore not only provides support for the walls of the deposit, but to some extent may also provide support for the roof of unbroken material.

3. The force of the explosive is not only expended in breaking ore down from the solid mass, but also serves to further fragment the broken material lying in the stope. In consequence, less secondary breaking of ore in the mine (as required, for example, to open plugged chutes) is necessary, and crushing of the ore taken from the mine is simplified. In addition, the ore broken down from the roof is better fragmented, because it is broken against the jagged upper surface of the previously broken ore.

The addition of waste fill at the top of the stope after all of the ore therein has been broken, at substantially the same rate as broken ore is withdrawn at the bottom of the stope, is the characteristic feature of the invention for providing support for the surrounding ground after com-

pletion of the ore-breaking operations. This procedure leads to the following advantages:

1. Ample support is provided for the ground without the need for excessive handling of waste fill and without the use of timbers.

2. In weak ground, the support provided by the added fill prevents spalling of waste material from the walls of the deposit, and prevents caving of the ground, which if it occurred would result in diluting and lessening the value of the broken ore.

3. In strong ground, the added fill prevents rock bursts that are apt to occur in large underground openings, especially at considerable depths. The new procedure for adding fill, especially when used in conjunction with the herein-described procedure for breaking the ore, makes it unnecessary to form any large open spaces underground at any stage of the mining operations, and so makes it feasible to conduct mining operations at much greater depths than have heretofore been possible in ground that is subject to rock bursts.

4. The added fill, of course, is highly effective for preventing surface subsidence during or after mining operations.

The adaptation of the new mining method described in conjunction with Fig. 5 has the following particular advantages:

1. It makes it possible to mine in a considerable number of closely spaced stopes and enables the mining operations in each stope to proceed independently of those in adjacent stopes. Most of the load involved in supporting the surrounding ground is borne by the broken ore and added fill, so that the partitions of ore in place may be very thin. If desired, even these thin partitions may be extracted by erecting timber partitions or cementing the added fill along the boundaries of the stope.

2. If applied to underground mining, this method permits substantially complete extraction of ore from large and extended ore bodies without caving or surface subsidence.

3. When applied to surface outcropping deposits, as particularly illustrated in Fig. 5, the new method may be used to supplant open-cut mining, or may be used in conjunction with open-cut mining to remove the valuable ore along the side slopes of the open cut without having to remove large amounts of waste ground or overburden to prevent caving of side slopes into the open cut. This of course results in increased recovery of ore with decreased mining of waste material from the side slopes.

Most adaptations of the new method to either underground or surface cropping deposits lead to the following general advantages:

1. A working pattern for the orebody that is independent of the number of solid block faces in juxtaposition may be developed.

2. Economic working of orebodies which when caved produce fragments of a size difficult to handle underground is facilitated.

In general, the new method may be applied advantageously to replace, or to be used in conjunction with, such heretofore known mining methods as shrinkage stoping, cut-and-fill stoping, top slicing, sublevel caving, block caving, and open-cut mining.

I claim:

1. The method of mining ore from an underground deposit in ground requiring support which comprises breaking the ore in a stope within the deposit sufficiently to permit its withdrawal from

said stope by gravity flow, forming the roof of the stope at an angle to the horizontal substantially as great as the angle of repose of available waste fill, introducing such waste fill into said stope at the top thereof, and continuously supplying such fill to the stope in substantially the same amount and at substantially the same rate as broken ore subsides from the top and is withdrawn from the bottom of said stope, whereby the walls and roof of the stope are at all times supported by broken ore or added fill.

2. In the mining of ore from a deposit in which ore in a stope in the deposit is broken and the broken ore is withdrawn from the bottom of said stope with consequent subsidence of its upper surface, the improvement which comprises forming the roof of the stope at an angle to the horizontal at least as great as the angle of repose of available waste fill, and adding such waste fill directly to the subsiding upper surface of the broken ore and continuing the addition of such waste fill continuously in substantially the amount required to maintain said stope full to the roof with broken material at all times.

3. The method of mining ore from a deposit which comprises marking off within the deposit a stope of substantial height and of less width than the width of the deposit, breaking the ore within said stope and withdrawing it from the bottom thereof, forming the roof of the stope at an angle to the horizontal at least as great as the angle of repose of available fill material, adding such waste fill at the top of the stope at substantially the same rate as the upper surface of the broken ore subsides therefrom and in amount sufficient to keep the stope full to the roof at all times with added fill, similarly working a horizontally adjacent stope within the deposit, and maintaining between the stopes a partition capable of preventing admixture by cross flow of fill added to one stope with ore broken in the adjacent stope.

4. The method of mining ore from an underground deposit which comprises breaking ore in a stope within the deposit, withdrawing the broken ore from adjacent the bottom of the stope, forming the roof of the stope at an angle to the horizontal substantially as great as the angle of repose of available fill material, and introducing such waste fill into the top of said stope through the apex of the angular roof thereof at a rate substantially equal to the rate at which broken ore is withdrawn from said stope and as its upper surface subsides therein, the added fill being at all times maintained in substantial contact with the roof of the stope so as to provide support therefor as well as for the stope side walls.

5. The method of withdrawing broken ore from an underground stope and providing support for the surrounding ground which comprises withdrawing the broken ore from the bottom of the stope and adding waste fill at the top thereof directly to the upper surface of the broken ore, said waste fill being added as the upper surface of the broken ore subsides and in amount sufficient to keep the stope substantially full of broken material at all times, the added fill being at all times maintained in contact with the roof of the stope so as to provide support therefor as well as for the stope side walls.

6. The method of mining ore from a deposit in ground requiring support which comprises forming a manway extending upwardly through the height of a stope within the deposit and an ore chute communicating with the deposit adja-

cent the bottom of said stope, drilling from the manway into the deposit above the chute, breaking the ore by blasting from the drill holes, withdrawing the broken ore through the chute only in controlled limited amount such that voids are created in the mass of broken ore without lowering its upper surface substantially out of contact with the overhanging unbroken ore, and continuing breaking of the ore in said manner to the top of the stope, the stope below the unbroken ore being maintained substantially full of broken ore at all times during ore-breaking operations.

7. In a method of mining ore from a stope containing broken ore in the lower portion thereof and unbroken ore above, involving blasting ore from the lower portion of the unbroken ore mass downwardly against said upper surface of the broken ore, the improvement which comprises performing the blasting operation while the upper surface of the broken ore is in contact with the overhanging unbroken ore, whereby the force of the blast further fragments the already broken ore as well as breaking a further quantity of ore.

8. The method of mining ore from a stope containing broken ore in the lower portion thereof and unbroken ore above, which comprises blasting ore from the lower portion of the unbroken ore mass downwardly against the upper surface of the broken ore, maintaining the upper surface of the broken ore at all times substantially in contact with the lower surface of the overhanging mass of unbroken ore so that no extended open space is permitted to form between the unbroken ore and the underlying broken ore, whereby the blasting operation contributes to further fragmentation of the already broken ore, then withdrawing sufficient broken ore from the lower portion of the stope to create fresh voids in the column of broken ore without creating any extended open space between its upper surface and the lower surface of the still unbroken ore, and repeating the sequence of operations.

9. The method of mining ore from a stope which comprises forming a manway extending upwardly through the stope, drilling substantially laterally from the manway into the lower portion of the mass of unbroken ore in the stope, blasting the ore downwardly from the drill holes, and withdrawing broken ore from the lower portion of the stope in controlled limited amounts sufficient only to create voids in the mass of broken ore without lowering its upper surface substantially out of contact with the lower surface of the still unbroken ore.

10. The method of mining ore from a stope which comprises forming a manway extending upwardly through the stope, maintaining the stope substantially full at all times of broken and unbroken ore with the upper surface of the column of broken ore in contact with the lower surface of the unbroken ore, and conducting all ore-breaking operations from working positions within the manway.

11. The method of mining ore from a deposit in ground requiring support which comprises forming a substantially vertical column of broken ore of considerable height within the deposit, forming a number of vertically spaced ore chutes communicating with and intermediate the ends

of the deposit, withdrawing ore from said column through a first of said chutes at a point well above the bottom of that part of the deposit to be worked, adding waste fill at the top of said column at substantially the same rate as broken ore is withdrawn so as to maintain at all times a full column of broken material, discontinuing withdrawal of broken ore through said first chute before the interface of broken ore and fill has subsided to the level where the angle from the chute to the laterally most remote part of said interface is less than about 70° to the horizontal, breaking the ore of any barrier between said first chute and the next lower chute, and continuing withdrawal of the ore from said column through said next lower chute.

12. The method of mining ore from a deposit in ground requiring support which comprises breaking the ore throughout the height of an upper stope within the deposit, forming an ore chute communicating with the bottom of the upper stope, withdrawing broken ore from said upper stope through said chute and adding waste fill at the top of said stope as the upper surface of broken ore subsides therein so that the stope is kept substantially full of broken material at all times, breaking the ore throughout the height of a second stope immediately below and communicating directly with said upper stope, discontinuing withdrawal of ore through the chute at the bottom of said upper stope before the interface of broken ore and fill has subsided to the level where the angle from said chute to the laterally most remote part of said interface is less than about 70° to the horizontal, forming a second chute at the bottom of said second stope and making further withdrawals of broken ore through said chute at the bottom of said second stope.

13. In extracting ore from a deposit in which a column of ore has been broken and is being withdrawn by gravity flow through a chute, and where waste fill is added at the top of said column as the upper surface of the broken ore subsides, the improvement which comprises discontinuing withdrawal of the broken ore through the chute before the interface between the broken ore and fill has subsided to the level where the angle from said chute to the laterally most remote part of said interface is less than about 70° to the horizontal, forming a second chute in communication with said column of ore and located at a point such that the angle between said second chute and the part of the interface laterally most remote from said second chute is appreciably greater than about 70°, and making any further withdrawals of ore by gravity flow through said second chute.

PHILIP B. BUCKY.
